UNITED STATES PATENT OFFICE.

FRANK L. FISHER, OF MILWAUKEE, WISCONSIN.

SMOKE-CONSUMING DEVICE FOR LOCOMOTIVES.

1,208,764.

Specification of Letters Patent. Patented Dec. 19, 1916.

Application filed March 16, 1916. Serial No. 84,719.

To all whom it may concern:

Be it known that I, FRANK L. FISHER, a citizen of the United States, and resident of Milwaukee, in the county of Milwaukee and State of Wisconsin, have invented certain new and useful Improvements in Smoke-Consuming Devices for Locomotives, and I do hereby declare that the following is a full, clear, and exact description 10 thereof.

The present invention relates to new and useful improvements in smoke consuming devices for furnaces, and is more particularly directed to that type of smoke consuming device for use on railway locomotives and including means for conveying the smoke and gases back through the fire-box.

A common disadvantage encountered in connection with smoke-consuming devices 20 of the present nature is that proper provision for the ultimate disposition of the gases under desired conditions is not had, and it is therefore primarily the object of the present invention to provide a positive 25 means for the escape of a certain amount of the gases from the furnace so that a sufficient supply of air may be had in the place thereof to promote proper combustion.

It is well known that a commingling of 30 steam from the exhaust of the pistons with the smoke will reduce the objectionable qualities of the smoke, and it is more specifically an object of the invention to permit the limited quantity of smoke above noted 35 to escape with the steam in such proportion as to be properly commingled therewith to reduce its objectionable features.

A further object resides in the provision 40 of means for adjusting the volume of smoke permitted to escape.

A still further object resides in the provision of means utilizing the back flow of combustion gases to the fire-box as a heating means in conjunction with the injector 45 mechanism.

With the above and other objects and advantages in view, the invention resides more particularly in the novel combination, arrangement and formation of parts more

particularly hereinafter described and particularly pointed out in the appended claims.

In the drawings Figure 1 is a partly diagrammatic side elevational view of a railway locomotive equipped with the present smoke consuming apparatus, and with the front portion of the locomotive broken away to more clearly disclose the structure. Fig. 2 is a transverse sectional view through the front end portion of the locomotive on the line 2—2 of Fig. 1, and showing the relation of the gas-conveying pipes thereto. Fig. 3 is a plan view of the distributor pipe arrangement associated with the fire-box. Fig. 4 is a sectional view on the line 4—4 of Fig. 1 taken longitudinally through one of the gas pipes and showing the heating arrangement for the injector means, Fig. 5 is an elevational view of the fan member, and Fig. 6 is a transverse sectional view on the line 6—6 of Fig. 5 through one of the blades of the fan member to show the gas outlet channel thereof.

Referring now more particularly to the accompanying drawings, 5 designates generally the shell of the locomotive engine, in the front end of which is formed the usual smoke chamber between the front wall 6 of the boiler and the front wall of the shell, and the usual gas flues 7 extend from the fire-box portion 8 of the shell to this chamber. The usual steam exhaust pipe 9 extends upwardly through this chamber in alinement with the smoke stack 10 thereof. The foregoing structure is conventional. 85

To provide for conveying the combustion gases back to the fire-box, a pair of pipes 11 communicate with the front bulged end of the shell, as shown more particularly in Fig. 2, and extend backwardly along the sides of the shell to points adjacent its rear end, from whence the pipes are downwardly offset to dispose their rear end portions adjacent the level of the grate and these rear end portions are provided each with a series 90 of outlet pipe sections 12 which communicate with and support opposite arms of a rectangular pipe frame 13, and the other

arms of this pipe frame are connected by a series of pipe sections 14 which are provided with jet nozzles 15 whereby the combustion gases are discharged evenly 5 throughout the entire area of the fire-box.

To provide for a division of the combustion gases in the front shell chamber, a cylindrical wall 16 is disposed in the chamber and connected at its inner end with the boiler 10 wall 6 and is at its outer end outwardly offset at 17 to engage the shell and thus form an annular chamber communicating with the smoke stack 10, the steam pipe 9 passing through this chamber. For providing a 15 forced draft of the gases, a shaft 18 is journaled axially in the chamber, preferably by suitable connection with the front wall of the chamber and the pipe structure 9, and this shaft carries a fan 19 and is driven 20 through the medium of a steam turbine 20 disposed in the chamber and suitably geared to the said shaft, this turbine being driven by steam conveyed from the usual "nigger head" 21 of the engine through a suitable 25 pipe 22 therethrough, this pipe being provided with a valve 23 whereby the operation of the turbine may be controlled. Connecting the outer ends of the blades of the fan 19 30 is an annular plate 24 and this plate slides in and closes an annular slot 25 formed in the cylindrical wall 16, and is provided adjacent the center of each blade with a passage 26. Each blade is provided in its working 35 face with a longitudinal groove 27 communicating at its outer end with a respective passage 26 and having one side inset to form a pocket, and further provided at its other side with a projecting flange 28 which serves to deflect the gases into the groove. Thus 40 upon rotation of the fan a certain amount of the gases will be caught in the grooves of the fan blades and projected into the annular chamber portion and will mix with the exhaust steam of the engine, and pass outwardly 45 through the smoke-stack, whereby a means is provided for an eventual elimination of the combustion gases, the proportion of gas which passes out in this manner being such as to commingle properly with the exhaust steam of the engine so as to reduce 50 the objectionable features of the gas, and a control of the amount of gas thus passing from the smoke-stack is had through the control of the fan drive means. In certain 55 instances it may be desired to procure a further escape of combustion gases through the smoke-stack, and to accommodate such instances the pipe 9 within the cylindrical wall 16 is provided with series of slots 29 60 which are normally covered by sleeves 30 and these sleeves may be slid to expose the slot and thus permit escape of combustion gases. Inasmuch as any means for procuring movement of the sleeves to uncover-

ing position may be had, no means is specifically shown. 65

The gases passing backwardly through the pipes 11 possess exceedingly great heat, and this feature is utilized in procuring a heating of the injector pipe which is shown in 70 the drawings as comprising a rear section 31 extending forwardly from the usual injector control mechanism 32, and a forward section 33 connected with the forward end of the boiler. The adjacent ends of these sections 75 are passed into the adjacent gas pipe 11, and are provided within the pipe with head chambers 34 which are connected by series of water tubes 35, to present a maximum heating surface. 80

I claim:

1. A smoke consuming device for furnaces including a fire box and a gas chamber, comprising a duct connecting said fire box and gas chamber to form a circuit for the gases, 85 said chamber being provided with an annular opening, a fan in the chamber, and an annular plate carried by the ends of the fan blades and closing said opening and provided with openings at the ends of the fan 90 blades.

2. A smoke consuming device for furnaces including a fire box and a gas chamber, comprising a duct connecting said fire box and gas chamber to form a circuit for the gases, 95 said chamber being provided with an annular opening, a fan in the chamber, an annular plate carried by the ends of the fan blades and closing said opening and provided with openings at the ends of the fan 100 blades, and said blades being provided with longitudinal pocket grooves in alinement with respective plate apertures.

3. A smoke consuming device for locomotive engines comprising the combination 105 with an engine shell including a fire-box portion and a gas chamber at its forward end, of said chamber being divided into sections, a smoke-stack communicating with one of the sections, a steam exhaust duct 110 communicating with said section, the combustion gases from the fire-box communicating with the other section, a duct connecting said other section with the fire-box, means for permitting escape of a limited amount of 115 gas from the last specified section to the first, said steam duct passing through the second specified section and having apertures communicating therewith, and means for closing said apertures. 120

4. A smoke consuming device for locomotive engines comprising the combination with an engine shell including a fire-box portion and a gas chamber at its forward end of an annular wall portion in said chamber dividing it into inner and outer sections, a smoke-stack communicating with the outer section, a duct communicating with the inner 125

section and with the fire-box, means permitting a limited amount of gas to pass from the inner section to the outer section, a steam duct passing transversely through the sections in alinement with the smoke-stack and communicating with the outer section there-
5 adjacent, apertures in the steam duct within

the inner section, and means for closing said apertures.

In testimony that I claim the foregoing I 10 have hereunto set my hand at Milwaukee, in the county of Milwaukee and State of Wisconsin.

FRANK L. FISHER.
